HARVEY HUBBELL, OF BRIDGEPORT, CONNECTICUT.

ATTACHMENT-PLUG.

1,180,648.

Specification of Letters Patent. Patented Apr. 25, 1916.

Application filed March 15, 1915. Serial No. 14,303.

To all whom it may concern:

Be it known that I, HARVEY HUBBELL, a citizen of the United States, residing at Bridgeport, county of Fairfield, State of Connecticut, have invented an Improvement in Attachment-Plugs, of which the following is a specification.

The invention relates to separable attachment plugs and has for its object to provide a plug of this character in which, while the connection shall be easy to make, it shall be impossible to make it except in one position of the contact blades; so that there can be no change in polarity. This I accomplish in the manner which I will now describe and then specifically point out in the claims hereunto appended.

In the accompanying drawing forming a part of this specification, Figure 1 is a view on an enlarged scale, partly in elevation and partly in section, illustrating the construction and operation of my novel plug; Fig. 2 an elevation of one of the base contacts and the corresponding contact blade detached; Fig. 3 an elevation of the other base contact and the corresponding contact blade detached; Fig. 4 a plan view of the base detached; Fig. 5 an elevation of the cap detached, and Fig. 6 is a plan view of the cap detached.

10 denotes the base and 11 the cap, both made of insulating material, and 12 the screw shell. These parts may be of any ordinary or preferred construction. 13 and 14 denote the base contacts which lie in recesses 15 in the base, and 16 and 17 the contact blades which project from the cap. These contact blades are adapted to be passed through slots 18 and 19 in the base and to engage the base contacts in recesses 15. The ends of the contact blades are shown as rounded and beveled for convenience in engagement and as provided on opposite edges with recesses 20. The base contacts each comprise spring plates adapted to receive the corresponding contact blade between them, one plate in each contact being provided with lugs or indentations 21 adapted to engage the recesses 20 in the corresponding contact blade.

The novelty of the present invention lies in the mode of making the plug non-reversible, that is, making it so that each contact blade can only be placed in engagement with

the base contact of corresponding polarity. 55 With this end in view I make contact blade 16 both longer and wider than contact blade 17 and make slot 18, which receives blade 16, longer than slot 19 which receives blade 17. In practice, the slots are made to just receive 60 the blades comfortably. The essential feature, however, is that slot 19, while receiving blade 17 freely, is made too short to receive blade 16. In order to facilitate the introduction of blade 16 into slot 18, I surround 65 the outer end of said slot with an elongated inwardly tapering depression 22 which serves to guide the blade into the slot. In making the connection, blade 16 only will at first come into contact with the base. The 70 position of the parts may then be changed without the slightest inconvenience even in the dark until blade 16 passes into the depression and then into slot 18, after which blade 17 will pass into slot 19 as a matter 75 of course.

In order to prevent a break upon one side before the break occurs upon the other side in disconnecting the members, or rather in order to make the break practically simultaneous on both sides, I make base contact 14 longer than contact 13 and cause it to extend farther down into the recess. In other words, the relatively long contact blade engages a relatively short base contact 85 and the relatively short contact blade engages a relatively long base contact.

Having thus described my invention I claim:

1. A separable attachment plug comprising a base having recesses, slots leading into said recesses, a relatively long base contact in one of said recesses, a relatively short base contact in the other recess and a cap having a relatively long contact blade adapted to engage the relatively short base contact and a relatively short contact blade adapted to engage the relatively long base contact, so that in disengaging the members the break will be practically simultaneous on 100 both sides.

2. A separable attachment plug comprising a base having recesses, contacts in said recesses and a relatively long and a relatively short slot leading into said recesses 105 respectively, the outer end of said longer slot being surrounded by an elongated inwardly tapering depression, and a cap hav-

ing contact blades corresponding in width with the length of the slots, said wider blade being longer than the other blade and adapted to first engage the depression in 5 making contact.

3. In a separable attachment plug, a base having recesses, contacts in said recesses and a relatively long and a relatively short slot leading into said recesses respectively, said 10 longer slot being surrounded by an elong-

gated inwardly tapering depression, substantially as described.

4. In an attachment plug, a cap having a relatively long and a relatively short contact blade, said longer contact blade being 15 also wider than the other blade, substantially as described.

In testimony whereof I affix my signature.

HARVEY HUBBELL.
